UNITED STATES PATENT OFFICE

110,398

DESIGN FOR A DISPLAY TRAY

Horace Lester Moseley, McAllen, Tex.

Application May 2, 1938, Serial No. 76,934

Term of patent 3½ years

To all whom it may concern:

Be it known that I, Horace Lester Moseley, a citizen of the United States, residing at McAllen, in the county of Hidalgo and State of Texas, have invented a new, original, and ornamental Design for a Display Tray, of which the following is a specification, reference being had to the accompanying drawing, forming part thereof.

I claim:

The ornamental design for a display tray, as shown.

H. L. MOSELEY.
